S. C. Barry
ATTORNEY

UNITED STATES PATENT OFFICE

ROBERT J. MARSHALL, OF ELMHURST, NEW YORK, ASSIGNOR TO NORTH AMERICAN SOUND AND TALKING PICTURE EQUIPMENT CORPORATION, OF NEW YORK, N. Y., A CORPORATION OF DELAWARE

MOUNTING FOR PHONOGRAPHIC PICK-UP DEVICES

Application filed March 8, 1929. Serial No. 345,253.

The present invention relates to improvements in devices for recording and reproducing sound for use in connection with apparatus for recording and reproducing moving pictures. More particularly it relates to the mounting of the pick-up recording device associated with the phonograph record. It is now common to provide a resilient connection between the turntable standard 5 and the base upon which the turntable is mounted, for the purpose of insulating the standard against vibration from the driving motor and other sources of vibration which would have an adverse effect on the tonal 10 quality of the sound reproduced or recorded.

In accordance with my present invention, I mount the pick-up or recording device upon a standard attached to the turntable standard whereby I avoid having either to rest the 20 support for the pick-up device upon a member apart from the table bearing the turntable standard or to provide separate insulating means between such standard and the main table.

25 My invention will be clearly understood from the following detailed description taken with the annexed drawing, in which the figure shows an illustrative embodiment of my invention.

30 In said drawing, 10 denotes a table to which is attached a phonographic turntable 15 by means of bolts 12, 12, a plurality of felt washers 14 being interposed between said standard and table as shown, such washers 35 being effective to insulate the standard 11 from vibrations acquired by the table 10 from the motor, not shown, for driving the turntable. The turntable proper denoted by 15 is mounted upon a vertical shaft 16 which is

40 journaled in standard 11, as shown. A drive shaft 17 is journaled in bearings 18, 19 attached to standard 11. Shaft 17 has thereon a worm 21 which is operatively connected to a worm-wheel 22. For preventing vibrations

45 arising from the operation of the worm and worm-wheel from being transmitted to the turntable 15, the following construction is provided: A collar 24 is attached to shaft 16 by means of a set screw 25 and has secured 50 therein a pair of studs 27, 27 having there-

on felt rings 28, 28 to receive which are provided recesses 29, 29 in the worm-wheel 22. A collar 30 secured to shaft 27 by set screw 31 is provided at the top of the worm-wheel, said collar 30 and collar 24 being separated from the worm-wheel 22 by means of felt washers 33, 34. In this manner a completely floating construction is provided for the worm-wheel 22 which effectively prevents vibrations from said wheel from being transmitted to the turntable 15.

Attached to one leg of standard 11 is an arm 35, said arm being secured thereto by means of bolts 36, 36. Arm 35 has a platform 38 adapted to receive the pick-up or recording device 39 which is operatively associated with the phonograph record 40, said device being joined to said platform as by a screw bolt 41.

It will be evident from the foregoing that I have provided a means for mounting the pick-up or recording device such that said device is effectively insulated from vibrations reaching same while making use of no other vibration insulating devices other than those necessary to the insulation of the turntable shaft.

I claim:

1. A device of the character described, a phonographic turntable comprising a standard, a support for said standard, means attaching same to said support, means for insulating said standard against vibration from said support, a sound recording or reproducing device adapted to be operatively associated with a record borne by said turntable, and a standard bearing said sound device attached to said turntable standard.

2. In a device of the character described, a phonographic turntable comprising a standard, a support therefor, means for driving said turntable, means attaching said turntable to said support, means for insulating said standard against vibration from said support, means for insulating said standard against vibration through said driving means, and a standard bearing said sound device attached to said standard of said turntable.

3. In combination with a phonographic turntable comprising a standard and having

means for insulating said turntable from vibration affecting sound which is either recorded or reproduced in connection with said turntable, a sound recording or reproducing device adapted to be operatively associated with a record borne by said turntable, and a standard bearing said device which is supported solely by said turntable standard.

10 In testimony whereof I have affixed my signature to this specification.

ROBERT J. MARSHALL.
